UNITED STATES PATENT OFFICE.

ETHEL M. PACE, OF VICKSBURG, MISSISSIPPI, ASSIGNOR OF ONE-HALF TO EDWARD R. O'NEILL, JR., OF NEW ORLEANS, LOUISIANA.

SOUND MODULATOR.

Application filed July 19, 1922. Serial No. 576,064.

To all whom it may concern:

Be it known that I, ETHEL MARTIN PACE, a citizen of the United States, residing at Vicksburg, in the county of Warren and State of Mississippi, have invented certain new and useful Improvements in Sound Modulators, of which the following is a specification.

This invention relates to an improved type of tone modulator and amplifier, which may be used in connection with phonographs and the like.

The primary object of this invention is the provision of a modulating device for use in connection with phonographs, whereby needless and annoying sounds, such as needle scratches, harsh metallic sounds, etc., may be eliminated, so that the reproduced sound emanating from the modulator may be full, clear and even.

A further object of this arrangement is the provision of tone modulating device adapted for use in connection with sound reproducing mechanisms, whereby the reproduced sound escapes through a tortuous path; sound waves being guided within the same and modulated so that scratches and other undesirable noises are eliminated therein, so that a clear and distinct sound is delivered to listeners.

A further object of this invention is the provision of a tone modulating member which may be utilized in connection with phonograph cabinets and so disposed therein in compact manner that the cabinet may be utilized for the storing of records and the like.

Other objects and advantages of this invention will be apparent during the course of the following detailed description.

In the accompanying drawing, forming a part of this specification, and wherein similar reference characters designate corresponding parts throughout the several views.

Figure 1 is a transverse cross sectional view taken through a cabinet type of phonograph, showing the improved modulator as mounted therein in section.

Figure 2 is a perspective view of the improved tone modulator.

In the drawing, wherein for the purpose

of illustration is shown the preferred embodiment of the improved tone modulator, the letter A designates the modulator, 55 which may be utilized in connection with a sound reproducing apparatus B, and mounted in a cabinet C.

The cabinet C, in general formation, is of the conventional type, including side 60 walls 10; bottom wall 11; rear wall 12; front wall 13; supporting platform 15 upon which the motor 16 and turn table 17 of the sound reproducer device B are mounted, and in which the tone arm 18 of the sound reproducing device B is movably connected; and a closure arrangement 20, hingedly connected to the rear wall 12 whereby the tone arm arrangement 18 and turn table 17 may be covered upon the supporting platform 70 15, as in the ordinary phonograph cabinet formation. The depending end 21 of the tone arm 18 extends into the large compartment 22 provided by the side, front and rear walls of the cabinet C, adjacent the 75 rear wall 12.

Generically, the improved tone modulator comprises a casing having a tortuous passageway therethrough and providing a constricted inlet opening which receives the 80 sound waves from the tone arm 18, the passageway from this inlet gradually enlarging in dimension, so that the passage-way through the tone modulator is of greatest dimension intermediate its inlet and outlet openings. The sound waves pass through the casing and are then led through a constricted outlet to a sound horn or similar arrangement.

Referring to the type of tone modulator A as is illustrated in the drawing, the same includes an inlet portion 25; an outlet portion 26; an intermediate portion 27; and may also include a delivery horn 28. The modulator is constructed of any light material, such as rose wood, and relatively thin. All joints of the parts thereof must be airtight and in particular those joints by which the inlet and outlet portions are connected to the intermediate portion.

The inlet portion 25 may be of polygonal cross section and includes a neck piece 30 providing the constricted inlet opening 31; said neck 30 being that portion which is

connected to the depending end of the tone arm connecting piece 21, so that the passageway 32 of the tone arm 18 is connected directly with the restricted inlet opening 31 of the passageway 33 of the inlet modulating portion 25. The inlet portion 25, from its neck 30 increases in cross sectional dimension in gradual manner outwardly to the marginal edge 35, so that the passageway 33 of the inlet modulator portion 25, in fact, increases in cross sectional dimension gradually away from the inlet opening 31.

The intermediate portion 27 which is the body of the modulator A, is preferably uniformly rectangular in cross section and open at its upper marginal edge 37. A concaved bottom 38 is provided which is attached to the lower edges of the relatively wide side walls 39 and the relatively narrow front and rear walls 40 and 41 respectively. A partition 42 is preferably disposed within the pocket of the modulator body 27, being attached to the side walls 39 as to divide the pocket of the intermediate portion 27 into passageways 45 and 46 upon opposite sides of the partition 42. The lower marginal edge 48 of the partition 42, however, terminate short of the arcuate bottom 38 so that the passageways 45 and 46 are in communication between the lower marginal edge 48 of partition 42, and the inclined surface of the arcuate bottom 38. The partition 42, of course, is cooperatively placed with respect to the inlet and outlet portions 25 and 26 respectively of the modulator A, so that the same aligns with the front wall 49 of the inlet modulator portion 25, when the latter is in position upon the intermediate portion 27, and thus placing the passageway 33 of the inlet portion 25 in alignment and communication with the passageway 45 of the modulator intermediate portion 27. To effect such result, the marginal edges 35 of the portion 25 are connected in air-tight relation in the upper marginal edges of the intermediate portion 27 about the passageway 45. The partition 42 may slope slightly, as illustrated in Figure 1 of the drawing, with respect to the front and rear walls 40 and 41, so that when the passageway 33 aligns with the passageway 45, the sound waves entering the modulator may pass downwardly through the passageways 33 and 45, and increase in fullness of tone by reason of the fact that the said aligning passageways increase in cross sectional dimension toward the bottom 38 of the modulator A.

Referring to the outlet portion 26, the same is of novel formation and has been provided so that the lower marginal edge 50 thereof may cooperate with the upper marginal edge of the intermediate portion 27 about the passageway 46. This outlet

portion 26 is provided with a relatively straight front wall 51, side walls 52, and a rear wall 53 which may be of arcuate formation and is connected by the side walls 52 with the front wall 51 in upwardly sloping relation therewith from the lower marginal edges 50, so that the passageway 55 provided by the outlet portion 26 is gradually diminished in dimension from the marginal edge 50 upwardly to the neck 56, wherein the passageway of the outlet portion 26 is most restricted. It can be readily understood that the sound waves passing upwardly through the aligning passageways 46 and 55, will be contracted prior to issuing into the sound horn 28.

The sound horn 28 may, of course, be included in the construction of the modulator A, and is connected at a constricted portion 58 with the neck portion 56 of the modulator A. The passageway or chamber 59 defined by the sound horn 28 increases in cross sectional dimension from the constricted end 58 outwardly toward the free end thereof, so that the sound waves emanating from the constricted neck 56 of the modulator A may be amplified prior to delivery to listeners.

As assembled within the cabinet B, the aligning passageways 33 and 45 are vertically disposed, as are also the aligning passageways 46 and 55. These aligning passageways are relatively long so that the arcuate bottom 38 of the modulator A is disposed adjacent the bottom wall 11 of the cabinet B. The modulator A is of such width as to its body portion 27, that the same occupies only about one half of the depth of the cabinet B, leaving room within the cabinet compartment 22 unobstructed so that a plurality of rack shelves 60 may be placed therein to provide compartments 61 for receiving records. The sound horn 28 is, of course, disposed so that the outlet thereof is through an opening 62 of the front wall 13 of cabinet C. To effect such result, the axis of the sound horn 48 is horizontally disposed just below the motor 16, and upwardly of the record receiving compartments 61.

The sound waves in pursuing their tortuous path through the modulator A whereby they are increased and decreased, will be delivered to an audience free of metallic sound and useless scratches in a full even tone. The modulator A not only modifies the tone of the reproducing device B, but also amplifies the same to a certain extent.

From the foregoing description of this invention, it can be readily understood that a modulator has been provided in which the sound waves are so treated therein as to produce the same in their natural manner as recorded.

Various changes in the shape, size and ar-

angement of parts may be made without departing from the spirit of the invention or scope of the claim.

I claim:

- 8 A phonograph horn comprising a body portion providing a relatively large chamber therein having an open top, and a bottom wall, a partition secured within said body portion and extending from the open top and terminating short of the closed bot-
- tom to sub-divide the chamber into two portions which have communication adjacent the bottom of the body portion, and inlet and outlet portions secured upon the body portion at substantially the same plane, said 15 inlet and outlet portions each being disposed over a sub-divided portion of the body portion chamber and having communication therewith.

ETHEL M. PACE.
